DRAFT RIGGING

Mark H. Martin, Reading, Pa., assignor to Birdsboro Steel Foundry & Machine Company, Birdsboro, Pa., a corporation of Pennsylvania

Application December 12, 1928
Serial No. 325,491

1 Claim. (Cl. 213—63)

My invention relates to draft rigging but more particularly to means for connecting together the coupler and yoke of draft rigging.

The general object of my invention is to provide novel draft rigging for a railway car characterized by the provision of a novel and improved construction of means for connecting the coupler to the yoke thereof in such manner as to permit angular movement of the said coupler, and also embodying means for operatively connecting the said yoke and coupler to the center sills of the said railway car.

It also is an object of my invention to provide novel draft rigging wherein a coupler of standard construction may be employed and wherein the coupler may be moved angularly with respect to the yoke, the construction and arrangement of the rigging being such as to cause buffing shocks imparted to the coupler to be centered upon the cushioning means of the draft rigging irrespective of the position of the said coupler relative to the said means.

A further object of my invention is to provide front draft stops of novel character for the center sills of a railway car, between which sills draft rigging is located.

Other objects and advantages from a practical standpoint will be pointed out in the detailed description thereof which follows or will become apparent from such description.

In order that the invention may be readily understood and its manifold practical advantages appreciated, reference may be had to the accompanying drawing in which a convenient embodiment thereof is illustrated. But it is to be understood that the invention is susceptible of being embodied in other forms of construction than that shown and that changes may be made in the details of construction without departing from the principle of the said invention.

In the said drawing,—

Fig. 1 is a view in horizontal sectional top plan showing draft rigging embodying my invention and the outer ends of center sills between which the said rigging is located.

Fig. 2 is a view in vertical longitudinal section taken on the line 2—2 of Fig. 1;

Fig. 3 is a view similar to that shown in Fig. 2, the coupler means shown in the latter being omitted in order to show more clearly the construction of the cheek plates secured to the sills;

Fig. 4 is a view in elevation on reduced scale of the outside of a fragmentary portion of a center sill near one end thereof, which sill embodies the construction shown in Fig. 3; and

Fig. 5 is a view in longitudinal vertical section showing a slightly modified construction of coupling.

Referring to the drawing, 1 designates the outer end portions of the center sills of a railway car between which draft rigging embodying the invention is located. The said draft rigging comprises a coupler of standard construction the stem 2 of which is connected to the arms 3 of a connecting member 4 by a key 5, which member is in turn pivotally connected to the arms 6 of the yoke of the draft rigging by means of the pin 7. The inner square end of the coupler stem fits in the opening between the arms 3, the inner surfaces of which are shaped to fit the adjoining surfaces of the stem 2. The outer ends of the key 5 extend through elongated openings or slots 8 provided in front draft stop members 10 which are riveted to the inner sides of the said sills. The said stop members are provided with outwardly extending flanges 11 which surround the openings 8 and are thickened at their inner end portions, as shown at 12 in Fig. 4, to provide end bearing surfaces of increased area for bearing against the inner ends of the slots 13 in the center sills, which slots are of the same shape as the exterior surfaces of the said flanges.

The inner end of the member 4 extends between the arms 6 of the yoke, as shown. The outer ends of the pin 7 extend through slots 14 provided in the said arms, and the said pin also extends through aligned openings formed in the three pivot lugs 15 and the two pivot lugs 16 of the member 4 and a swivel block 17 respectively, which lugs intermesh as shown. The swivel block is located between the arms 6, as shown in Fig. 2. The said pin is held in position by the retainer 18. The inner plane face of the swivel block 17 abuts or contacts with cushioning mechanism of known construction indicated diagrammatically by dot and dash lines 19. The said cushioning mechanism may embody a follower plate 20 with which the said swivel block engages. But as will be understood, the type of cushioning mechanism in which a separate follower plate is not used, may be employed in lieu of that which is shown, in which case the swivel block will contact directly with the cage thereof. When the rigging occupies the position shown, the follower 20 abuts or contacts with the inner flanged ends 21 of the front draft stop members.

In the operation of the rigging the coupler and the member 4 are moved to various positions about the pin 7 as an axis while buffing and draft shocks cause longitudinal movements of the coupler, the 110

member 4, pin 7, swivel block 17 and follower 20 relative to the yoke. Such longitudinal movements are permitted by the slots 14 in the arms of the yoke. The buffering shocks always are centered upon the cushioning means 19 by the swivel block and follower irrespective of the position of the coupler and the member 4. The coupler is supported in known manner near its forward end by the transverse member 23 formed integrally with the striker casting 24 and provided with the usual wear plate 25.

The swivel block 17 is guided by longitudinally extending flanges 27 formed on the stop members 10 and also by ribs 28 formed on the plates of said stop members and located intermediate the flanges 27. Referring to Figs. 1 and 3, it will be observed that the rib 28 shown therein extends forwardly and merges with the curved portion of an inwardly extending flange 29 which partially surrounds the slot 8. The flanges 29 and portions of the ribs 28 taper outwardly to permit the desired angular movement of the member 4 between the stop members 10, as will be understood. The flanges 21, 27 and 29 and the ribs 28 greatly strengthen the stop members 10 and cause forces which are imposed on the members 10 to be distributed over large areas of the sills to which they are secured.

It should be remarked that it has been the practice heretofore to construct draft rigging and front draft stops therefor in such manner that the inner ends of the said stops have been located in a plane including the inner end of the coupler stem. In other words, in prior constructions the

said stops generally are located at the points where the flanges 29 are located in the construction shown herein. It therefore will be obvious that a construction embodying my invention is superior to those devised heretofore, because thin sections of metal are avoided thereby and the loads which are imposed on the stop members are distributed over larger areas of the center sills upon which they are mounted.

In Fig. 5 I have shown a modified construction wherein the connecting member 4 is provided with two pivot lugs 33 instead of three, and the swivel block 17 has three pivot lugs 34 instead of two, this arrangement of the lugs being a reversal of that shown in Fig. 2.

Having thus described my invention, what I claim and desire to secure by Letters Patent is:

In a draft rigging, a coupler, a yoke, a connecting member interposed between the said coupler and the said yoke, said member being provided with a pair of spaced parallel arms between which the said coupler extends, a key having an intermediate portion connecting the said coupler to the said arms, and means for pivotally connecting the said member to the said yoke, said means having a 100 slidable connection with said yoke whereby the said coupler and the said connecting member are movable longitudinally relatively to the said yoke in combination with center sills having longitudinal slots passing outer portions of the key and 105 shoes fastened to the slots, said shoes fitting the slots and making longitudinal slide connections with extended portions of the key.

MARK H. MARTIN.
